UNITED STATES PATENT OFFICE.

JOHN J. O'BRIEN AND JOHN P. WAGGONER, OF ROANOKE, VIRGINIA.

RAIL-JOINT.

1,205,253.

Specification of Letters Patent.

Patented Nov. 21, 1916.

Application filed March 3, 1916. Serial No. 81,965.

To all whom it may concern:

Be it known that we, JOHN J. O'BRIEN and JOHN P. WAGGONER, citizens of the United States, residing at Roanoke, in the 5 county of Roanoke and State of Virginia, have invented new and useful Improvements in Rail-Joints, of which the following is a specification.

This invention relates to improvements 10 in means for connecting the meeting ends of railway rails.

In carrying out our invention it is our purpose to provide means arranged upon and connected with the angle joint bars for 15 the rails and underlying the rails at the meeting edges thereof whereby the rails may be adjusted vertically to maintain the same in proper and in positive alinement.

It is also our purpose to provide angle 20 bars which are reinforced and strengthened at the central portion thereof, the said central portions being subjected to the greatest amount of strain incident to the jar and shock to which they are subjected when the 25 wheels of the rolling stock pass over the ends of the rails and thus materially add to the life of the rails and the safety of the joint.

A still further object of the invention is 30 to provide an angle joint bar with centrally arranged depending lugs which will have a tendency to reinforce the rails and which also serve as seats for adjustable wedge plates that underlie and contact with the 35 base of the rails at the meeting edges thereof and whereby the ends of the rails may be vertically adjusted and held in such adjustment.

It is a still further object of the invention to provide the angle bars at the joint 40 of a rail with depending lugs having openings to receive wedge plates one of which overlies the other, and the said wedge plates being arranged to support the ends of the 45 rails, to provide means upon one of the plates which co-acts with the other plate for adjusting the plates longitudinally and locking the same in such adjustment, and to further provide means for locking the plates 50 together.

With these and other objects in view, the improvement resides in the construction, combination and arrangement of parts set forth in the following specification and falling within the scope of the appended claims. 55

In the drawings: Figure 1 is a top plan view of two rails connected in accordance with the present invention, Fig. 2 is a side elevation of the same, Fig. 3 is a transverse sectional view approximately on the line 60 3-3 of Fig. 2, Fig. 4 is a perspective view of one of the wedge plates, Fig. 5 is a similar view of the other wedge plate, Fig. 6 is a perspective view illustrating an ordinary angle bar provided with a central reinforcing and wedge plate supporting lug, and Fig. 7 is a perspective view of the lug detached. 65

In the drawings the rails are designated by the characters R, and the angle bars by 70 the numerals 1. Both of the angle bars are of similar construction and are connected to the rails by the usual nuts and bolts therefor. The central connecting nuts and bolts are received in pockets 2 provided at the 75 outer surfaces of the angle bars by central reinforcing ribs 3 and end ribs 4 spaced a suitable distance from the central ribs 3. These ribs, as illustrated in the drawings, are formed with both the vertical and horizontal plates of the angle bars and the ribs are provided only at the central portion for the reason that from experience it has been found that the ordinary angle bars are most susceptible to breakage at the central portion thereof which is incident to the violent 80 shock to which they are subjected by the wheels of the rolling stock passing over one of the rails onto the other rail. The horizontal members of the angle bars 1 below the reinforcing ribs 3 and 4 are provided each with a depending lug 5, and each of said lugs is centrally formed with a substantially rectangular opening 6. 85

The numerals 7 and 8 designate truss 90 plates which are adapted to rest one upon the other and which have their contacting faces beveled. Thus it will be noted that each of the plates 7 and 8 is in the nature of a wedge. The plate 7 has its thickened 95 100

- end provided with a downturned flange 9 and the plate 8 has both of its ends provided with down turned flanges, indicated by the numerals 10 and 11 respectively.
- 5 The openings 6 are sufficient to admit of the insertion of the plate 8 therethrough so that the flanges 10 and 11 lie against the outer faces of the lugs 5 of the respective angle bars 1. Thereafter the plate 7 is inserted
- 10 through the opening 6, its flange 9 being disposed adjacent the flange 10 of the plate 8. The flange 9 has an opening 12 within which is arranged a headless bolt 13, one end of the bolt being received in a threaded depression or pocket 14 in the outer face of the flange 10 of the plate 8, while nuts 15 and 16 respectively are threaded upon the bolt 13 and are arranged to contact with the opposite faces of the flange 9.
- 15 20 By adjusting the nuts 15 and 16 it will be noted that the plate 7 may be moved longitudinally in either direction over the plate 8 and as a consequence adjust the meeting ends of the rails R—R in a vertical direction, so that the heads of the rails will be maintained in positive alinement. The nut 15 may be first adjusted upon the bolt 13, and the nut 16 screwed upon the said bolt 13 in a homeward direction, causing the said
- 25 30 nut 16 to contact with the outer face of the flange 9, which movement of the said nut will force the plate 7 over the plate 8, the movement of the plate 7 in this direction being limited by the contact of the inner face of the flange 9 with the nut 15. It will be apparent that the plate 7 may be adjusted in an opposite direction by first loosening the nut 16 and then screwing the nut 15 against the inner face of the flange 9 until
- 35 40 the outer face of the flange 9 is brought into engagement with the nut 16.

The flange 11 of the plate 8 is provided with a central recess 17, and the plate 7 is provided with an elongated opening 18 which is arranged to communicate with the recess 17 and also to receive a wedge key 19. The key when inserted through the opening 18 is received in the depression 17 of the plate 8 and will of course contact with one of the walls provided by the opening 18 of the plate 7, and the lower and reduced end of the same may be bent to contact with the edge of the flange 11 or if desired the wedge key 19 may be provided with a plurality of spaced transverse openings 20 whereby a securing element, in the nature of a cotter pin or the like may be passed to lock the wedge key in its properly adjusted position and to permit of the withdrawal of the wedge key when it should be found desirable to separate the plates 7 and 8 from the angle bars.

In Fig. 6 we have illustrated an ordinary angle bar which is indicated by the numeral 21 and which has centrally secured to the

horizontal flange thereof the angular or horizontal portion 22 of a lug member 23, the vertical portion of the said lug member depending below the angle bar and the same is centrally provided with a substantially rectangular opening 24, similar to the opening 6 in the lugs 5 of the angle bars 1 and for a similar purpose. By the arrangement illustrated in Figs. 6 and 7 of the drawings it will be noted that the lug 23 may be attached to an ordinary angle bar 21 by rivets or the like and that the lug will materially reinforce the said angle bar at the central portion thereof as well as accommodate truss members in the nature of wedge plates similar to the wedge plates 7 and 8.

70 75 80 From the above description, taken in connection with the accompanying drawings, the simplicity of the device, as well as the advantages thereof, will, it is thought, be perfectly apparent to those skilled in the art to which such invention appertains without further detailed description.

Having thus described the invention, what we claim is:

1. In a means for connecting the meeting ends of rails, angle bars upon the opposite sides of the rails and connected therewith, reinforcing ribs connecting the horizontal and vertical flanges of the angle bars at the central portions thereof and surrounding the central connecting means for the angle bars, wedge plates associated with the angle bars and underlying the rails, means for adjusting the wedge plates, and means for locking the adjusted wedge plates.

90 95 100 105 110 115 120 125 2. In a means for connecting the meeting ends of rails, angle bars, lug members secured to the angle bars and depending centrally therefrom, wedge plates one overlying the other and passing through central openings in the lugs disposed to engage with the flanges of the rails at the meeting ends thereof, means upon one of the wedge plates co-acting with the other wedge plate for adjusting the wedge plates, and a removable key for locking the adjusted plates.

3. In a means for connecting the meeting ends of rails, angle bars upon the opposite sides of the rails and connected with the rails, each of said angle bars having a central depending lug, a truss member comprising two lapping wedge plates passing through openings in the lugs and supporting the rails at the meeting ends thereof, the upper wedge plate having its thick end formed with a depending flange, the lower wedge plate having both of its ends provided with depending flanges which are disposed to contact with the outer faces of the opposite lugs, a headless bolt passing through an opening in the flange of the upper wedge plate and having one of its ends received in a threaded pocket in one of the

- flanges of the lower wedge plate, nut members upon this bolt and contacting with the opposite sides of the flange of the upper wedge plate, a wedge key passing through 5 an opening in the upper wedge plate and received in a depression in the second flange of the lower wedge plate, and means for locking the said wedge key upon the plates.

In testimony whereof we affix our signatures in presence of two witnesses.

JOHN J. O'BRIEN.

JOHN P. WAGGONER.
